[57] CLAIM

The ornamental design for a holder for neck ties or similar articles, as shown.

DESCRIPTION

FIG. 1 is a left side top and front isometric view of a holder for neck ties or similar articles showing our new design in neck tie insertion position;

FIG. 2 is a front elevational view thereof in gravity oriented position;

FIG. 3 is a left side elevational view thereof, the right side being a mirror image;

FIG. 4 is a sectional view taken in the direction of the arrows on line 4—4 of FIG. 2;

FIG. 5 is a sectional view taken in the direction of the arrows on line 5—5 of FIG. 2;

FIG. 6 is a sectional view taken in the direction of the arrows on line 6—6 of FIG. 2.
